CLAIM

The ornamental design for a lighting device, as shown and described.

DESCRIPTION

FIG. 1 is a top-side perspective view of the lighting device; FIG. 2 is a bottom-side perspective view of the lighting device;

FIG. 3 is a top view of the lighting device;

FIG. 4 is a bottom view of the lighting device;

FIG. 5 is an enlarged side view of the lighting device, from the left side of the views in FIGS. 3 and 4;

FIG. 6 is an enlarged side view of the lighting device, from the right side of the views in FIGS. 3 and 4;

FIG. 7 is a further side view of the lighting device; and, FIG. 8 is a further side view of the lighting device.

The ornamental design which is claimed is shown in solid lines in the drawings. The broken lines in the drawings are for illustrative purposes only and form no part of the claimed design.
